UNITED STATES PATENT OFFICE.

ALLISON A. PRATT AND JOHN ZOLLINGER, OF NEW YORK, N. Y., ASSIGNEES OF ONE-
THIRD TO ALLISON A. PRATT, ONE-THIRD TO JOHN ZOLLINGER, AND ONE-THIRD
TO HENRY J. HEMMENS, ALL OF NEW YORK, N. Y.

SIPHON-HEAD.

1,137,530.

Specification of Letters Patent. Patented Apr. 27, 1915.

Application filed April 12, 1913. Serial No. 760,661.

To all whom it may concern:

Be it known that we, ALLISON A. PRATT, a citizen of the United States, and JOHN ZOLLINGER, a citizen of Switzerland, both 5 residents of the city of New York, borough of Manhattan, in the county and State of New York, have invented a new and Improved Siphon-Head, of which the following is a full, clear, and exact description.

10 The invention relates to containers, containing soda water and other liquids under pressure, and its object is to provide a new and improved siphon head arranged to permit of conveniently opening or closing it 15 without the use of the elaborate mechanisms now generally employed for the purpose. In order to accomplish the desired result, use is made of a spout mounted to rock in the cap of the head and controlling the out- 20 flow of the liquid.

A practical embodiment of the invention is represented in the accompanying drawings forming a part of this specification, in which similar characters of reference indicate corresponding parts in all the views.

Figure 1 is a sectional side elevation of the siphon head as applied and showing the spout in normal closed position; Fig. 2 is a similar view of the same and showing the 30 spout in open position; and Fig. 3 is a sectional plan view of the same on the line 3—3 of Fig. 1.

On the neck A' of a bottle or other container A is secured in any suitable manner 35 a cap B provided in its upper end with a tubular bearing C of rubber or other elastic material into which fits the inlet member D' of a spout D having an angular outlet member D² extending downwardly from the 40 upper end of the inlet member D'. The inner end of the inlet member D' of the spout D extends into a conical bore B' formed in the cap B below the bearing C, and the lower end of the bore B' terminates in a 45 flaring mouth B², as plainly indicated in Figs. 1 and 2. In the lower end of the inlet member D' is screwed or otherwise secured a head E supporting a gasket E' of rubber or other suitable elastic material and engaging 50 the mouth B² at the junction with the bore B' so that the head E and the gasket E' form a closure for the bore B' to normally close the same. The lower end of the inlet member D' of the spout D is provided

with an opening D³ opening into the conical bore B' above the closure consisting of the gasket E' and the head E. It will be noticed that when the user exerts a lateral pressure on the upper projecting end of the outlet member D² of the spout D then the 60 spout D rocks in the elastic bearing C as the fulcrum, and in doing so one side of the gasket E' is compressed while the other side of the gasket moves away from the wall of the mouth B², so as to open the mouth B² 65 at this side (see Fig. 2) to establish communication with the bore B' and the opening D³ to allow the liquid under pressure in the bottle A to pass through the usual siphon tube F and its head F' into the open 70 side of the bore B'. The liquid passes from the bore B' through the opening D³ and through the spout D into a glass or other receptacle held at the end of the outlet member D². The head F' of the siphon tube F 75 is in register with the mouth B² of the bore B' and the said head is preferably seated on a gasket G of rubber or other material and which also extends between the upper end of the neck A' and the inside of the 80 cap B to form a tight joint between the parts mentioned. It will be noticed that the resiliency of the bearing C normally holds the spout D in the position illustrated in Fig. 1, so that the gasket E' is seated in the 85 mouth B² thereby closing the entrance to the bore B' and the opening D³. The pressure of the liquid in the siphon tube F is exerted against the under side of the head E so that the gasket E' is firmly seated in the 90 mouth B² to prevent leakage of the liquid, but when the spout D is pressed sidewise at its upper end it rocks so as to open communication between the siphon tube F and the spout D to allow the discharge of the 95 liquid from the container. As soon as the pressure is released the spout D swings back to its normal position owing to the resiliency of the bearing C.

In order to limit the swinging movement 100 of the spout D use is made of a stop H held on the inlet member D' directly above the bearing C to engage the upper end of the cap B, as will be readily understood by reference to the drawings.

The siphon head shown and described is 105 very simple and durable in construction and composed of comparatively few parts not

liable easily to get out of order. It will also be noticed that the usual complicated mechanisms employed for opening and closing siphon heads are entirely dispensed with.

5 Having thus described our invention, we claim as new and desire to secure by Letters Patent:

- 10 1. A siphon head for containers provided with a cap, an elastic tubular bearing held in the upper end of the said cap, a spout having an inlet member and an angularly disposed outlet member, the said inlet member being mounted in the said bearing and having an opening therein, and a closure held on the inner end of the inlet member of the said spout below the opening and normally closing the cap, the said closure moving into open position on rocking the spout.
- 15 2. A siphon head for containers, comprising a cap provided in its lower end with a conical seat, a tubular bearing of resilient material arranged in the upper end of the said cap, a siphon tube in register with the said seat, a spout having an inlet member and an outlet member, the inlet member having an inlet opening and extending through the said bearing into the said conical seat, and an elastic closure held on the inner end of the said inlet member and normally closing the said seat.
- 20 30 3. A siphon head for containers, comprising a cap provided in its lower end with a conical seat, a tubular bearing of resilient

material arranged in the upper end of the said cap, a siphon tube in register with the said seat, a spout having an inlet member and an outlet member, the inlet member having an inlet opening and extending through the said bearing into the said conical seat, an elastic closure held on the inner 40 end of the said inlet member and normally closing the said seat, and a stop on the said inlet member of the spout and adapted to engage the cap to limit the rocking movement of the spout.

4. A siphon head for containers, comprising a cap provided in its lower end with a conical seat, a tubular bearing of resilient material arranged in the upper end of the said cap, a siphon tube in register with the 50 said seat, a spout having an inlet member and an outlet member, the inlet member having an inlet opening and extending through the said bearing into the said conical seat, and a closure held on the inner end 55 of the said inlet member and provided with a head and an elastic gasket held on the said head and engaging the said seat.

In testimony whereof we have signed our names to this specification in the presence 60 of two subscribing witnesses.
